TOILET TISSUE DISPENSER
Boyd B. Casteel, 2134 Confederate Place,
Louisville, Ky.
Filed Feb. 19, 1964, Ser. No. 343,776
4 Claims. (Cl. 242—55.3)

This invention relates to personal hygiene and more particularly to toilet tissue dispensers for use in bathrooms and the like.

While the toilet tissue holder usually found in the bathroom of the average home or public rest room is admittedly a low cost device to install, it does have serious disadvantages and limitations if the family is a large one or if the public rest room is in much demand.

The main disadvantage of the toilet tissue holders now on the market is the lack of provisions for storing extra rolls of the tissue. This is particularly noted in public rest rooms where attendants are not always available when needed.

It is, therefore, the first object of this invention to provide a toilet tissue dispenser in which can be stored any number of rolls of toilet tissue as well as the roll of tissue that is in position and ready for instant use.

Another object of this invention is to provide a toilet tissue dispenser that has all of its operating mechanism as well as the rolls of toilet tissue totally enclosed within an eye-pleasing structure suitable for setting in any bathroom or public rest room.

Another object of this invention is to provide a toilet tissue dispenser that, while able to hold a number of rolls of toilet tissue, still takes up but a minimum of space.

Another object of this invention is to provide a toilet tissue dispenser that can be rotated about a fixed base according to the installation requirements of the room in which it is placed.

Another object of this invention is to provide a toilet tissue dispenser having dispensing mechanism that will not bind under any condition and is, therefore, as foolproof as one can make a device of this nature.

Another object of this invention is to provide a toilet tissue dispenser that does not contain any electrically operated mechanism.

Still another object of this invention is to provide a toilet tissue dispenser that can be given any color exterior finish desired, since the case of the device is not limited to construction from any one kind of material.

Still other objects reside in the combination of elements, arrangements of parts, and features of construction, all as will be more fully pointed out hereinafter and disclosed in the accompanying drawing wherein:

FIGURE 1 is a perspective view of this invention opened to show the rolls of toilet tissue stored therein.

FIGURE 2 is a side view of this invention broken open to show its internal construction.

FIGURE 3 is a sectional view of this invention taken along line 3—3 of FIGURE 2.

FIGURE 4 is a sectional view of this invention taken along line 4—4 of FIGURE 2.

Similar reference characters refer to similar parts throughout the several views of the drawing.

Having reference now to the drawing in detail, this invention comprises a square flat base 10 supported by countersunk rollers 11 and having a ballbearing-mounted supporting rod 12 projecting vertically upward from the center thereof and rotatably supporting the subbase 13 on top of which is mounted the toilet tissue cabinet 14 which is provided with a door 15 through which the rolls of toilet tissue 16 are placed, as is illustrated in FIGURE 1 of the drawing.

2

The aforesaid toilet tissue cabinet 14 actually rotates on a plurality of rollers 17 that are recessed within the upper surface of the aforesaid flat base 10, as is clearly shown in FIGURE 2 of the drawing, where it is also seen that this invention contains a toilet tissue roll support plate 18 that is swingably mounted on the upper end of the link 19 by the screw 20. The lower end of the same link is secured to the inner end 21 of the horizontally disposed rod 22 by the screw 23 while the outer end 10 of the same rod projects through the vertical and centrally located slot 24 in the front panel 25 of the cabinet 14. A lifting handle 26 is secured to the outer end of the aforesaid horizontally disposed rod 22, as is carefully shown in FIGURES 1 and 3 of the drawing. FIGURE 15 2 illustrates the supporting mechanism for the horizontally disposed rod 22. This supporting mechanism embodies a pair of spaced holders 27 mounted on the tracks 28 by means of a plurality of rollers 29 thereby permitting the entire assembly, including the aforesaid toilet tissue roll support plate 18, to be manually moved upward in the cabinet 14 by the already mentioned lifting handle 26.

A pair of spaced and parallel guide bars 30 are secured to the upper end of the rear panel 31 of the cabinet 14. 25 The upper end of each one of the guide bars 30 is contoured to a roll of toilet tissue which is raised up to the same by the already described lifting mechanism. When a roll of toilet tissue has been raised up this far it is in the curved top 32 of this invention which is provided with 30 the mechanism for holding the roll of toilet tissue in place ready for use. This last mechanism of which there is one on each side of the curved top 32 comprises a hinged member 33 having a holding member 34 projecting at right angle therethrough and also through an opening 35 in the side 36 of the curved top 32. A knob 37 is located on the outer end of the holding member 34 while the inner end 38 of this member has the configuration of a paraboloid, as one can see on looking at FIGURE 3 of the drawing. The front end of the curved 35 top 32 of this invention is, of course, open as shown in FIGURE 1 in order that the roll of toilet tissue 16 may become available for use in the usual manner. The curved top 32 is actually flat at its uppermost point in order to provide a seat for the ash tray 39, while a U-shaped handle 40 is located on one or more sides of this invention as indicated in FIGURE 1 of the drawing, which also shows in FIGURE 2 that the previously described toilet tissue support plate 18 is further guided in place in this invention by a free-turning wheel 41 that rolls 45 along the center of the aforesaid rear panel 31 of the cabinet 14, while a bar magnet 42 that is in the shape of a disk is embedded in each one of the hinged members 33 and which by coming into contact with the steel circle 43 that is embedded in the side 36 of the curved top 32 50 will firmly hold the hinged member(s) in place when the members are in closed or holding position.

From the foregoing it will now be seen that there is herein provided an improved toilet tissue dispenser which accomplishes all the objects of this invention, and others, including many advantages of great practical utility and commercial importance. As many embodiments may be made of this inventive concept, and as many modifications may be made in the embodiment hereinbefore shown and described, it is to be understood that all matter herein is 60 to be interpreted merely as illustrative and not in a limiting sense.

I claim:

1. A toilet tissue dispenser of the character described, comprising a base, rollers countersunk into the underside of the base and secured thereto, a subbase, means including a vertically disposed ball bearing rotatably securing the subbase to the base, a vertically disposed cabinet

secured to the subbase, a plurality of rollers recessed into the upper surface of the base to assist in supporting the subbase, the cabinet adapted to have a plurality of rolls of toilet tissue placed therein, means adapted to raise a roll of toilet tissue to the upper end of the cabinet, means to hold said roll in said position and an opening in the uppermost part of the cabinet to expose the roll that is in the upper end of the cabinet.

2. A toilet tissue dispenser of the character described, comprising a base, rollers countersunk into the underside of the base and secured thereto, a subbase, means including a vertically disposed ball bearing rotatably securing the subbase to the base, a vertically disposed cabinet secured to the subbase, a plurality of rollers recessed into the upper surface of the base to assist in supporting the subbase, the cabinet adapted to have a plurality of rolls of toilet tissue placed therein, a toilet tissue support plate within the cabinet, means to raise said support plate to raise a roll of tissue to the upper end of the cabinet, means to hold said roll in said position and an opening in the uppermost part of the cabinet to expose the roll that is in the upper end of the cabinet.

3. A toilet tissue dispenser of the character described, comprising a base, rollers countersunk into the underside of the base and secured thereto, a subbase, means including a vertically disposed ball bearing rotatably securing the subbase to the base, a vertically disposed cabinet secured to the subbase, a plurality of rollers recessed into the upper surface of the base to assist in supporting the subbase, the cabinet being high enough to have a plurality of rolls of toilet tissue placed therein in a vertical column, a toilet tissue roll support plate within the

5 cabinet beneath the column, means to raise said support plate to raise the upper roll of tissue to the upper end of the cabinet, means to hold said roll in said raised position and an opening in the upper most part of the cabinet to expose the roll that is in the upper end of the cabinet.

10 4. A toilet tissue dispenser of the character described, comprising a base, rollers countersunk into the underside of the base and secured thereto, a subbase, means including a vertically disposed ball bearing rotatably securing the subbase to the base, a vertically disposed cabinet secured to the subbase, a plurality of rollers recessed into the upper surface of the base to assist in supporting the subbase, the cabinet being high enough to house a plurality of rolls of toilet tissue placed therein in a vertical column, a toilet tissue roll support plate within the cabinet beneath said column, means to raise said support plate to raise a roll of tissue to the upper end of the cabinet, means including hinge mechanism and a magnet to hold said roll in said position and an opening in the uppermost part of the cabinet to expose the roll that is in the upper end of the cabinet.
